UNITED STATES PATENT OFFICE.

WILLIAM LEE HANLEY, JR., OF BRADFORD, PENNSYLVANIA.

TUNNEL KILN.

Application filed August 30, 1926, Serial No. 132,393. Renewed August 8, 1928.

My invention consists in the novel features hereinafter described, reference being had to the accompanying drawings, which illustrate one embodiment of the same, and a slight modification thereof, selected by me for purposes of illustration, and the said invention is fully disclosed in the following description and claims.

The object of my invention is to produce a single tunnel kiln, especially adapted for the firing of bricks and other coarse clay products. In the construction of such a kiln, it is desirable to employ a simple and economical construction in order to minimize the very large initial cost of the kiln, and to keep down the expenses of upkeep and repair. In carrying my present invention into effect, I employ a single tunnel structure, which is entirely free from longitudinal flues or passages, so that it can be very cheaply constructed. The central portion of the tunnel kiln constitutes the firing zone, and is provided with furnaces preferably arranged in a row along one side, or along both sides of the firing zone, which discharge their products of combustion directly into the firing zone, so as to impart the greatest possible heat to the goods and economy of fuel, the products of combustion being withdrawn from the firing zone preferably adjacent to each furnace and conducted away from the kiln, the heat of such products of combustion being recovered and utilized for drying the products before firing, for heating air to be supplied to the furnaces, or burners, and for other purposes. This prevents the products of combustion from passing into the other portions of the kiln, which comprise a preheating zone at one end of the firing zone, and a cooling zone at the other end of the heating zone, goods transporting means being provided for conveying the goods through the entire length of the kiln, successively through the preheating zone, firing zone, and cooling zone, and comprising preferably, a plurality of tunnel cars extending the entire length of the kiln, and running upon suitable tracks. In order to raise the incoming, unfired goods gradually to a temperature approximately that of the entering end of the firing zone, to preheat them, and effect the water-smoking and oxidization of the products, and at the same time utilize a portion of the heat of the furnaces for this purpose, I provide means for delivering air to the cooling zone where it comes in con-

tact with the hot fired products, after they leave the firing zone, thus effecting the recovery of a suitable amount of heat from the fired products, the heating of the air so introduced and facilitating the cooling of the fired products, and this highly heated air from the cooling zone is withdrawn therefrom preferably at the end adjacent to the firing zone where the temperature of the fired products is greatest, and is conducted preferably by means outside of the kiln to the preheating zone, where it is introduced and brought into contact with the unfired ware, for the purpose of raising the temperature thereof and supplying oxygen thereto, to effect the preheating, water-smoking and oxidization of the ware, before it reaches the firing zone. I also prefer to provide means for withdrawing the air, together with vapors, gases, etc., produced in these operations, in the preheating zone, so as to prevent the possibility of scumming or staining the brick during the preheating thereof.

I also prefer to provide the furnaces, or burners, with regulating means, and to provide the passages through which the products of combustion are withdrawn from the firing zone, and which are located preferably between adjacent furnaces, with controlling or regulating means, so that the temperature of the firing zone may be regulated and controlled. I preferably so regulate the temperature of the firing zone that at its entering end it will maintain substantially the temperature to which the unfired ware has been preheated, in passing through the preheating zone, the temperature of the firing zone gradually increasing throughout the length thereof to the hottest portion, which is located adjacent to the discharge end of the firing zone, in accordance with what is termed a rising heat curve, which may be of any desired characteristic, according to the regulation of the individual regulating devices, before mentioned. My invention provides an extremely simple tunnel kiln therefor, the initial cost of which is small, and which is entirely without internal complications, contributing both to low initial cost and low cost of upkeep or repair, and great economy and efficiency of operation is secured by advantageously utilizing practically all of the heat supplied by the furnaces, portions of which are recovered from the burned or fired ware, and used in the preheating zone, and portions of which are re-

covered from the products of combustion and utilized for air heating and drying purposes.

In the accompanying drawings, which illustrate one embodiment of my invention, and a slight modification thereof,

Fig. 1 is a diagrammatic, plan view of a single tunnel kiln embodying my invention, and showing a drier for the unfired products arranged in connection therewith and heated from the waste heat of the kiln furnaces, or burners.

Fig. 2 is a horizontal, sectional view of a kiln drawn to an enlarged scale, and partly broken away.

Fig. 3 is a vertical section through the pre-heating zone of the kiln.

Fig. 4 is a transverse, vertical section through the firing zone of the kiln.

Fig. 5 is a horizontal plan view of a slightly modified form of single tunnel kiln, provided with a row of furnaces at opposite sides of the firing zone.

Fig. 6 is a transverse vertical section through the firing zone of the kiln, illustrated in Fig. 5.

Referring to the form of the invention illustrated in Figs. 1 to 4, inclusive, the kiln comprises a continuous single track tunnel, of which the central portion, indicated at A, is the firing zone, from the opposite ends of which the two end sections of the tunnel extend, the section, B, being the preheating zone, and the section, C, being the cooling zone. A single line of tracks, indicated at 1-1, extends longitudinally through the entire length of the kiln, and in operation is occupied by a continuous line of tunnel cars, 2, each carrying a carload of bricks, or other coarse clay or ceramic products to be fired, indicated at 3, in dotted lines in Fig. 3. It will be understood that the kiln provides a longitudinal goods space, or passage, extending from one end of the kiln to the other, without either transverse or longitudinal partitions, and without any longitudinal flues. The end portions, B, and C, of the tunnel, are of very simple construction, and comprise the side walls, 4-4, and the crown, 5, which may be of ordinary brick, or any other suitable material. The central portion, A, of the tunnel, which comprises the firing zone, is also a single tunnel structure, which is preferably made of slightly greater width than the end portions of the kiln, and comprises the side walls, 4^a-4^a, and crown, 5^a-5^a, the side walls being spaced further apart in order to accommodate a unitary bridge wall, or walls, 6, between the goods space and the furnaces, or burners, which are preferably arranged in a row on one side of the firing chamber, as shown in Figs. 1 to 4, or on both sides, as shown in Figs. 5 and 6. In the form shown in Figs. 1 to 4, where only one row of furnaces, or burners is employed, only one bridge

wall is employed, arranged on one side only of the goods space, indicated at D, in each of the several zones. The furnaces for firing the goods may be of any usual or desired character and adapted for the consumption of any preferred fuel. In the present instance I have shown the furnaces, 7, provided with a burner, 8, for a mixture of gas and air supplied by pipes, 9 and 10, respectively, under the control of independent valves, 11 and

70

12, respectively, for each burner, so that each individual furnace may be independently regulated, and a predetermined heat curve may be maintained, increasing from the entering end of the firing zone to the discharging end thereof. For example, a temperature of 900°

75

to 1400° F., more or less, may be maintained at the entering end of the firing zone, the temperature of the different portions of the firing zone increasing, more or less gradually, to a temperature of 1800° to 2100° F., more or less, at the discharge end adjacent to the cooling zone, C. Where other forms of furnaces are employed, the means for independently regulating each furnace will vary with

80

the character of fuel employed. The products of combustion discharged from the furnace, or burners, are conducted upward through passages, indicated at 13, between the side wall of the kiln and the adjacent bridge wall, 6, and the upper ends of the bridge walls are preferably provided with inwardly extending portions at the top, as indicated at 6^a, and if desired, also at one or

85

more points below the top of the bridge wall, as indicated at 6^b, in order to discharge the hot products of combustion into the upper part of the goods space within the firing zone, and cause them to descend through the goods on the cars instead of between the goods and the bridge wall, as far as possible. The bridge wall, 6, is connected with the adjacent wall, 4^a, of the kiln, on opposite sides of each furnace, or burner, by a transverse partition, indicated at 20, which does not extend as high

90

as the top of the firing chamber, and preferably has its upper edge considerably below the top of the bridge wall, so that the discharge passages, 13, merge into a common discharge passage, 13^a, above the tops of the transverse partitions, 20.

95

Means are provided, preferably between adjacent furnaces, for withdrawing the products of combustion from the firing zone. To this end, the inner face of the bridge wall is

100

preferably provided adjacent to the level of the lower row, or rows, of goods on the cars, with a plurality of exhaust ports, 14, preferably in alignment with the respective transverse partitions, 20, each of said ports being connected by a transverse eduction pipe, or passage, 15, extending outside of the firing chamber, and connected to a header,

105

16, or collecting flue, extending longitudinal-ly of the firing chamber, each of the educ-

110

17, or collecting flue, extending longitudinal-ly of the firing chamber, each of the educ-

115

18, or collecting flue, extending longitudinal-ly of the firing chamber, each of the educ-

120

19, or collecting flue, extending longitudinal-ly of the firing chamber, each of the educ-

125

20, or collecting flue, extending longitudinal-ly of the firing chamber, each of the educ-

130

tion ports and the passage connected therewith, being provided with regulating means. In this instance I have shown each of the eduction pipes, 15, provided with a controlling valve, 17, for illustrative purposes, but obviously any form of damper or regulating means, which will withstand the high temperature of the products of combustion, will be employed. The eduction pipes, 15, 5 may extend horizontally through the kiln wall, or may be connected in any other manner, with the collecting flue, 16, which may be located upon or underneath the ground, and below the kiln, if desired. For greater 10 clearness, I have shown the collecting flue in this instance located outside of the firing zone, in alignment with the passages, 15, and ports, 14, but these details of construction may be varied to suit the ideas of different 15 constructors and the general character of kiln construction. In order to secure the withdrawal of the products of combustion, means are provided to create a suction, or rarefaction in the collecting pipe, and the eduction 20 ports or passages connected therewith. Any suitable device for this purpose can be employed. In the present instance, I have shown a fan or air forcing device, indicated at 18, and provided with an injector nozzle 25 discharging into the collecting flue, 16, as indicated in dotted lines at 19, but any other form of means for producing suction may be employed.

The products of combustion discharged 30 into the collecting flue, 16, are very highly heated, and a considerable portion of this heat can be advantageously utilized for heating the drier, or driers, in which the ceramic products are dried, preliminary to firing them 35 in the kiln. These products of combustion can also be employed for heating air to supply the furnaces, and for other purposes. In the present instance, for example, I have shown the collecting flue, 16, discharging into 40 a recuperator, 21, of any desired type, provided with separate air passages, 22, through which air, as from a fan, 23, or other air forcing device, may be caused to pass, and become highly heated, said air passing out through 45 a pipe, 24, which may be connected with the air pipe, 10, which supplies air to the heating burners for the firing zone, as shown in Fig. 1, and this air pipe may also be connected directly with the drier and discharge 50 clean, heated air into the same, to assist in the drying of the ceramic products, as indicated in said figure. The products of combustion themselves are preferably conducted, after leaving the recuperator, by a pipe, 25, 55 to heating pipes, indicated at 26, within the drier, out of communication therewith, in which they give up a large percentage of their remaining heat, to the air circulating in the drier, after which they are passed, by 60 a pipe, 27, to a stack, 28, and discharged 65 into the atmosphere. Obviously, if the draft of the stack is sufficient to provide the necessary suction in the collecting flue, 16, and eduction passages connected therewith, the injector fan, 18, or other equivalent means, 70 may be dispensed with.

The cooling zone, C, of the kiln, is provided with a plurality of induction ports, 29, through which fresh air from the outside of the kiln is introduced into the cooling zone 75 at different points longitudinally thereof, along its entire length, or a portion of its length. The cooling zone is also provided with a plurality of eduction ports, indicated at 30, for withdrawing this air after it has 80 been highly heated, by convection and radiation, as from the cooling fired products on the cars in the cooling zone, the said eduction ports being located at different points longitudinally of the cooling zone throughout a 85 portion, or all of its length, and either on the same side as the induction ports, or opposite sides, as preferred. In the present instance, in Fig. 1, I have shown the induction ports located adjacent to the discharge end of the 90 kiln, remote from the firing zone, and supplied by a plurality of pipes, 31, provided with regulating devices, 32, from a header, 33, connected with a fan, 34, or other air forcing device. The eduction ports, 30, are shown 95 located adjacent to the firing zone, where the fired products on the cars are at the highest temperature after leaving the firing zone, said eduction ports being connected with 100 eduction pipes, 35, provided with regulating valves, 36, and connected by a header, 37, which is connected with a transverse flue, 105 preferably located outside of the kiln, and indicated at 38, for transferring the heated air withdrawn from the cooling zone, to a header, 39, adjacent to the preheating zone, B, said header, 39, being provided with inlet pipes, 40, discharging into the preheating zone, preferably at separated points throughout its length, and each having a regulating 110 valve, 41. In order to insure the withdrawal of the heated air from the cooling zone, and its discharge into the preheating zone, continuously, I prefer to employ a suitable form 115 of air forcing device, and in the present instance I have shown a fan, indicated at 42, located in the transfer pipe, or passage, 38, for example. The transfer pipe may be located under ground, or properly protected by insulating material, to prevent loss of 120 heat. In this construction a very large proportion of the heat of the fired products can be recovered and used for heating large quantities of air drawn or discharged into the cooling zone, and facilitating the cooling of the ware, the said heated air being transferred to and distributed throughout the preheating zone to effect the preheating, water-smoking and oxidization of the unfired ware. In introducing the air into the cooling zone at 125 130

points near its outer end, and withdrawing this air at points adjacent to the firing zone, the temperature of the air will be gradually raised, as it passes along the fired products, 5 in a general direction toward the firing zone, becoming highly heated and being withdrawn at the highest temperature, the last instruments of heat being imparted to it from ware which has just issued from the firing 10 zone. The introduction of this heated fresh air into the preheating zone, provides the necessary oxygen for the oxidization and water-smoking of the brick, and in order to withdraw from the preheating zone the vapors and gases produced in the preheating, 15 oxidization and water-smoking of the brick, or other products, I preferably provide the preheating zone with a plurality of eduction ports, indicated at 43, arranged at different 20 points longitudinally of the preheating zone and connected with an eduction pipe, 44, communicating with a header, 45, which is in turn connected by a pipe, 46, with suction producing means, as a stack, 47, or exhaust 25 fan, for positively withdrawing the air, vapors, and gases from the preheating zone, and further insuring a continuous supply of clean, hot air containing the requisite quantity of oxygen in the preheating zone. The 30 eduction pipes, 44, will preferably be provided with regulating means, as valves, 48, and by regulating these valves and the air inlet valves, 41, the desired graduated temperature may be maintained within the pre- 35 heating zone, longitudinally thereof, so as to gradually raise the temperature of the ware from the time it enters the preheating zone until it passes into the firing zone, so as to obtain the most effective results without 40 checking or cracking, or otherwise injuring the ware, and so that when the ware passes into the entering end of the firing zone, it will have been brought to a temperature substantially equal to that within the adjacent 45 portion of the firing zone, so that the subsequent step of firing may be effected by the further and graduated increase in temperature prescribed by the heat curve maintained in the firing zone.

50 In Figs. 5 and 6 I have shown a slightly modified form of my invention, in which it is embodied in a kiln, the firing zone of which is provided with a row of furnaces on each side. In these figures, parts corresponding to 55 those shown in Figs. 1 to 4, inclusive, are given the same reference numerals with 100 added, and where the parts are identical, they will not be again described. As shown in Fig. 6, the firing zone is provided with two 60 bridge walls, 106, and two rows of furnaces, 107, in this instance heated by burners, 108, in the same manner as the single row of furnaces shown in the other figures, and the parts are constructed and operate substantially as 65 hereinbefore described, except that in this in-

stance the products of combustion are discharged from both rows of furnaces into the top of the goods space, indicated at D', within the firing zone, and pass down through the goods and thence out through the eduction 70 ports, 114, in the opposite bridge walls, and through the eduction passages, 115, to the collecting flues, or headers, 116, on opposite sides of the firing zone. Obviously, each of these headers could be connected to a superheader 75 in the same manner as the header, 16, in Fig. 1, for example, but I prefer to connect the two headers, 116, together, by a transverse pipe, 116^a, and pass the products of combustion from both rows of furnaces through a single recuperator, 121, and thence by pipe, 125, to heating passages, 126, in the drier, and thence to a stack, 128, by a pipe, 127. The recuperator in such case is supplied with air by a fan, 123, which is passed through heating passages, 122, and the air is conducted by pipe, 124, to the drier, portions of the heated air being conducted to the respective air pipes, 110, for supplying the burners of the furnaces of both rows. This avoids unnecessary duplication.

In this instance the firing zone is indicated at A', the preheating zone, at B', and the cooling zone, at C'. The cooling zone is supplied with fresh air from a fan, 134, for example, through a header, 133, and regulated in the pipe, 131, provided with valves, 132, and the cooling zone is also provided with eduction pipes, 135, connected to a header, 137, which is in turn connected with the transfer pipe, or passage, 138, in which may be located a fan or other suction means, 142, for transferring the heated air from the cooling zone to a header, 139, connected by regulated pipes, 140, with the preheating zone at intervals throughout its length, under the regulation of suitable regulating valves, 141. The preheating zone is also provided with eduction pipes, 144, provided with regulating valves, 148, and connected with a header, 145, which is in turn connected by a pipe, 146, with a stack or other exhausting means, 147. It will be understood that the operation of this form of kiln is exactly the same as that previously described, except that the firing zone is provided with two rows of furnaces instead of one.

What I claim and desire to secure by Letters Patent is:—

1. A single tunnel kiln, comprising among its members a centrally located firing zone, provided with a series of furnaces discharging their products of combustion into the firing zone, means for withdrawing the products of combustion directly from the firing zone without permitting appreciable longitudinal flow, a preheating zone extending longitudinally from one end of the firing zone, a cooling zone extending longitudinally from the other end of the firing zone, a single line of goods conveying means extending 120

- through all of said zones, means for supplying air from the outside of the kiln to the cooling zone for heating it from the hot fired products therein, and means for withdrawing 5 said heated air from the cooling zone and discharging it into the preheating zone for preheating, oxidizing and water-smoking the unfired products therein.
2. A single tunnel comprising among its 10 members, a centrally located firing zone, provided with a series of furnaces discharging their products of combustion into the firing zone, independent means for controlling said furnaces, for maintaining a gradually increasing temperature from one end of the firing zone to the other, means for withdrawing the products of combustion directly from the firing zone without permitting appreciable longitudinal flow, a preheating zone located 15 at one end of the firing zone, a cooling zone located at the other end of the firing zone, a single line of goods conveying means extending through all of said zones, means for introducing air into the cooling zone in contact 20 with the heated, fired products therein, and means for withdrawing said air heated by the latent heat of said fired products and transferring it to and introducing it into the preheating zone for preheating, oxidizing and 25 water-smoking the unfired products during 30 their passage to the firing zone.
3. A single tunnel kiln, comprising among its members, a centrally located firing zone, provided with a series of furnaces discharging 35 their products of combustion into the firing zone, means for withdrawing the products of combustion from the firing zone, a preheating zone extending longitudinally from one end of the firing zone, a cooling 40 zone extending longitudinally from the other end of the firing zone, a single line of goods conveying means extending through all of said zones, means for supplying air from the outside of the kiln to the cooling zone for 45 heating it from the hot fired products therein, the preheating zone being provided with a plurality of air inlets having independent regulating means, located at different points longitudinally of the preheating zone, and 50 means for withdrawing the heated air from the cooling zone and distributing it to the said inlet passages to preheat, oxidize and water-smoke the unfired products, whereby 55 said inlet passages may be regulated to effect the gradual raising of the temperature of the unfired products as they are moved in a direction toward the firing zone.
4. A single tunnel kiln, comprising among its members, a centrally located firing zone, provided with a series of furnaces discharging 60 their products of combustion into the firing zone, means for withdrawing the products of combustion from the firing zone, a preheating zone extending longitudinally from one end of the firing zone, a cooling 65 zone, means for supplying air from the outside of the kiln to the cooling zone for heating it from the hot fired products therein, said means being located at different points longitudinally of the cooling zone, eduction passages communicating with the cooling zone and located at different points longitudinally thereof, means connected with said eduction ports for withdrawing the heated air from the cooling zone and transferring it to the preheating zone, and means for discharging said heated air into the preheat-
- extending longitudinally from the other end of the firing zone, a single line of goods conveying means extending through all of said zones, means for supplying air from the outside of the kiln to the cooling zone for heating it from the hot fired products therein, the preheating zone being provided with a plurality of air inlets having independent regulating means, located at different points longitudinally of the preheating zone, and means for withdrawing the heated air from the cooling zone and distributing it to the said inlet passages, to preheat, oxidize and water-smoke the unfired products, whereby said inlet passages may be regulated to effect the gradual raising of the temperature of the unfired products as they are moved in a direction toward the firing zone.
5. A single tunnel kiln, comprising among its members, a centrally located firing zone, provided with a series of furnaces discharging their products of combustion into the firing zone, means for withdrawing the products of combustion from the firing zone, a preheating zone extending longitudinally from one end of the firing zone, a cooling zone extending longitudinally from the other end of the firing zone, a single line of goods conveying means extending through all of said zones, means for supplying air from the outside of the kiln to the cooling zone for heating it from the hot fired products therein, means for withdrawing the heated air from the cooling zone and transferring it to and distributing it into the preheating zone to preheat, oxidize and water-smoke the unfired products therein, said preheating zone being provided with a plurality of eduction passages and means connected therewith for withdrawing air laden with the vapors and gases produced by oxidation and water-smoking from the preheating zone.
6. A single tunnel kiln, comprising among its members, a centrally located firing zone, provided with a series of furnaces discharging their products of combustion into the firing zone, means for withdrawing the products of combustion from the firing zone, a preheating zone extending longitudinally from one end of the firing zone, a cooling zone extending longitudinally from the other end of the firing zone, a single line of goods conveying means extending through all of said zones, means for supplying air from the outside of the kiln to the cooling zone for heating it from the hot fired products therein, said means being located at different points longitudinally of the cooling zone, eduction passages communicating with the cooling zone and located at different points longitudinally thereof, means connected with said eduction ports for withdrawing the heated air from the cooling zone and transferring it to the preheating zone, and means for discharging said heated air into the preheat-

ing zone at different points longitudinally thereof.

7. A single tunnel kiln, comprising among its members, a centrally located firing zone, provided with a series of furnaces discharging their products of combustion into the firing zone, means for withdrawing the products of combustion from the firing zone, a preheating zone extending longitudinally from one end of the firing zone, a cooling zone extending longitudinally from the other end of the firing zone, a single line of goods conveying means extending through all of said zones, means for supplying air from the outside of the kiln to the cooling zone for heating it from the hot fired products therein, said means being located at different points longitudinally of the cooling zone, eduction passages communicating with the cooling zone and located at different points longitudinally thereof, means connected with said eduction ports for withdrawing the heated air from the cooling zone and transferring it to the preheating zone, means for discharging said heated air into the preheating zone at different points longitudinally thereof, the air inlet passages and eduction passages of the cooling zone being provided with independent regulating means, and independent regulating means for controlling the admission of said heated air at said different points longitudinally of the preheating zone to establish and maintain gradually increasing temperatures therein from the entering end of the preheating zone, in a direction toward the firing zone.
8. A single tunnel kiln, comprising among its members, a centrally located firing zone, provided with a series of furnaces discharging their products of combustion into the firing zone, means for withdrawing the products of combustion from the firing zone, a preheating zone extending longitudinally from one end of the firing zone, a cooling zone extending longitudinally from the other end of the firing zone, a single line of goods conveying means extending through all of said zones, means for supplying air from the outside of the kiln to the cooling zone for heating it from the hot fired products therein, said means being located at different points longitudinally of the cooling zone, eduction passages communicating with the cooling zone and located at different points longitudinally thereof, means connected with said eduction ports for withdrawing the heated air from the cooling zone and transferring it to the preheating zone, means for discharging said heated air into the preheating zone at different points longitudinally thereof, the air inlets for the cooling zone being located adjacent to the delivery end thereof, and the eduction passages of the cooling zone being located adjacent to the firing zone whereby the air is caused to travel lengthwise of the cooling zone and to become gradually heated, and is withdrawn from the

cooling zone at the highest temperature therein.

9. A single tunnel kiln, comprising among its members, a centrally located firing zone, provided with a series of furnaces discharging their products of combustion into the firing zone, means for withdrawing the products of combustion from the firing zone, a preheating zone extending longitudinally from one end of the firing zone, a cooling zone extending longitudinally from the other end of the firing zone, a single line of goods conveying means extending through all of said zones, means for supplying air from the outside of the kiln to the cooling zone for heating it from the hot fired products therein, said means being located at different points longitudinally of the cooling zone, eduction passages communicating with the cooling zone and located at different points longitudinally thereof, means connected with said eduction ports for withdrawing the heated air from the cooling zone and transferring it to the preheating zone, means for discharging said heated air into the preheating zone at different points longitudinally thereof, independent regulating devices for controlling the inlet of said heated air at said points, eduction passages connected with said preheating zone and located at different points longitudinally thereof, independent regulating means therefor, and means connected with said eduction passages for withdrawing the heated air admitted thereto laden with vapors and gases produced by the heating, oxidation and water-smoking of the ware.
10. A single tunnel kiln, comprising among its members a centrally located firing zone, provided with a series of furnaces discharging their products of combustion into the firing zone, means for withdrawing the products of combustion directly from the firing zone without permitting appreciable longitudinal flow, a preheating zone extending longitudinally from one end of the firing zone, a cooling zone extending longitudinally from the other end of the firing zone, a single line of goods conveying means extending through all of said zones, means for supplying air from the outside of the kiln to the cooling zone adjacent to the discharge end thereof for heating said air from the hot fired products therein, and means for withdrawing said heated air from the cooling zone adjacent to the end thereof nearest the firing zone, and transferring said air so withdrawn to and discharging it into the preheating zone for preheating, oxidizing and water-smoking the unfired products therein.
11. A single tunnel kiln, comprising among its members a centrally located firing zone, provided with a series of furnaces discharging their products of combustion into the firing zone, means for withdrawing the

products of combustion from the firing zone, a preheating zone extending longitudinally from one end of the firing zone, a cooling zone extending longitudinally from the other end of the firing zone, a single line of goods conveying means extending through all of said zones, said cooling zone being provided with a plurality of air inlets adjacent to the discharge end of said zone and arranged at different points longitudinally thereof, said cooling zone being also provided with eduction apertures at separated points longitudinally thereof and located adjacent to the

end of the cooling zone nearest the firing zone, and means for withdrawing the heated air 15 from the cooling zone through said eduction apertures at the points of highest heat in said zone, and discharging said highly heated air into the preheating zone adjacent to the end thereof nearest the firing zone, and at 20 other separated points longitudinally thereof for preheating, oxidizing and water-smoking the unfired products therein.

In testimony whereof I affix my signature.

WILLIAM LEE HANLEY, JR.
